(57) CLAIM

I claim the ornamental design for a swimsuit top, as shown and described.

DESCRIPTION

FIG. 1 is a front view of a swimsuit top on a model showing my new design.

FIG. 2 is a rear view of the swimsuit top of FIG. 1.

FIG. 3 is a right-side view of the swimsuit top of FIG. 1.

FIG. 4 is a left-side view of the swimsuit top of FIG. 1.

FIG. 5 is a front view of the swimsuit top of FIG. 1 in an unworn state; and,

FIG. 6 is a rear view of the swimsuit top of FIG. 1 in an unworn state.

The evenly spaced broken lines in the figures illustrate environmental subject matter and form no part of the claim.

1 Claim, 6 Drawing SheetsFIG. 1

FIG. 2

FIG. 3

FIG. 4

FIG. 5

FIG. 6
